UNITED STATES PATENT OFFICE

WALTER E. WEGNER, OF DENVER, COLORADO

DOORSTOP

Application filed June 4, 1932. Serial No. 615,403.

This invention relates to improvements in door stops and has reference more particularly to a device especially well adapted for use with garage doors and similar large and heavy doors.

It is well known that unless some means is provided for holding garage doors in open position while the automobile is taken out of and driven into the garage more or less trouble is experienced by the doors blowing shut and accidents sometimes happen from this cause.

It is the object of this invention to produce a simple and substantial door stop mechanism that can be easily put in place and which will automatically latch the door in opening position.

Another object of this invention is to produce a device of the type specified which shall be of such construction that it can be readily applied to doors of different sizes and which, in addition to holding the door in fully open position, is equally well adapted to hold the door in an intermediate position.

A further object of this invention is to produce a door stop that shall be provided with a gripping device that can readily be disconnected by a simple pull on a chain or cord and which will remain in disconnected or inoperative condition, until the door is fully closed when it will automatically return to operative position.

A still further object of this invention is to produce a device in which the door shall be connected to the device by resilient means so as to permit a limited amount of movement without producing excessive strains.

This invention, briefly described, consists in a tubular member having one end provided with means for pivotally attaching it to the top member of the door frame. The free end of the tubular member is provided with a gripping means and telescopically connected with the tubular member is a rod. The outer end of this rod is connected with the door by means of a bracket and the gripping means is so constructed that it will permit the rod to be pulled outwardly from the tubular member, but will latch it against inward movement. The gripping means is provided

with a latch mechanism that will hold the gripping means inoperative while the door is being moved to closed position and which will automatically be released when the door has reached the closed position.

Having thus briefly described the invention, the same will now be described in detail, and for this purpose reference will be had to the accompanying drawing in which the preferred embodiment of the invention has been illustrated, and in which:

Fig. 1 is a side elevation of a door showing the same in closed position with the improved door stop attached thereto;

Fig. 2 is a view looking down upon the door and showing the same in open position;

Fig. 3 is a view partly in section showing the lower end of the tubular member and the top of the gripping device, the parts being shown in the position they occupy when the door is closed;

Fig. 4 is a section taken on line 4—4, Fig. 3, and shows the gripping device in normal position;

Fig. 5 is a view similar to that shown in Fig. 4, but shows the gripping device held in inoperative position; and

Fig. 6 is a transverse section taken on line 6—6, Fig. 5.

In the drawing reference numeral 1 designates one of the vertical members of a door frame while reference numeral 2 indicates the top member of the door frame. The door which has been indicated by reference numeral 3 is secured to the vertical door frame by means of hinges 4. The door stop which forms the subject of this invention consists of a tubular member 5 which may be a piece of gas pipe and which has attached to its upper end a curved fitting 6 which may be a forty-five degree elbow or a special fitting designed for this purpose. Member 6 has a headed projection 7 that extends through an opening in the bracket 8 and this bracket is secured to the inner side of frame member 2 by means of screws or bolts 9. Secured to the free end, which in this case is the lower end of member 5, is a gripping device. This gripping device consists of a tubular body member 10 which may be a brass casting or made

of some other suitable material. Member 10 has one end provided with a threaded opening 11 with which the lower end of pipe 5 is connected in the manner shown in Figs. 4 and 5. A recess 12 extends into one side of member 10 to a point substantially in line with the roots of threads 11. The other end of member 10 is provided with an opening 13 through which a rod 14 extends. This rod extends into the interior of pipe 5 and is of such a size that it will move freely in the opening in the pipe. The sides of member 10 extend upwardly and are separated at the end where connection is made with pipe 5 so as to form an opening 15 for the reception of one end of a latching member 16. Latching member 16 is held in place by means of a pivot pin 17 which permits it to rotate to some extent about this pin as a center. The other end of member 10 has a notch 18 in which the free end 19 of the detent lever normally rests. The under side of the end 19 is curved as indicated at 20 so as to form a cam surface and rod 14 has secured to it a cam member 21 having a frusto-conical surface 22, which serves to raise the detent lever 16 when the parts are in the position shown in Fig. 4. The lower side of member 10 is provided with a slot 23 through which a gripping plate 24 extends. This plate has an opening 25 through which the rod 14 extends in the manner shown in Figs. 4 to 6. A spring 26 surrounds the rod 14 and has its ends abutting one side of plate 24 and one end of the recess 33 in member 10. This spring is normally under compression and exerts a force that holds the gripping plate in the position shown in Fig. 4. The outer end of plate 24 has an arm 27 that extends at right angles and to which a chain 28 or a cord is connected. By exerting a pull on the chain 28 the plate can be rocked about its fulcrum until the end that is located underneath lever 16 comes into the notch 29 as shown in Fig. 5, whereupon it will be held in this position by lever 16. It is apparent that when the gripping plate is in the position shown in Fig. 4, it will permit the rod 14 to be extended with respect to the pipe 5, but will resist any action tending to move the rod 14 into the pipe. When the gripping plate is in the position shown in Fig. 5, rod 14 can be moved freely in either direction. From Fig. 4 it will be seen that the inner end of rod 14 has been provided with an opening 30 to which one end of a coiled tension spring 31 is connected. The other end of spring 31 is anchored to a pin 32 located near the upper end of member 5. The spring tends to move the rod 14 inwardly so as to collapse the two members, but is not of sufficient strength to offer any appreciable resistance against the opening of the door. When this spring is used it should be of sufficient strength to at least partially close the door after the grip-

ping means has been moved into the position shown in Fig. 5.

Let us now assume that a device constructed in the manner shown on the drawing and described herein is attached to the upper frame member of a door frame and to a door in the manner shown in Figs. 1 and 2. When the door is closed the parts are in the position shown in Fig. 1, but as the door is opened, rod 14 is pulled outwardly from the pipe 5 and is held against return movement by the gripping plate 24. Wherever the door is released, it will remain open because it cannot move to closed position against the action of the gripping means. After the automobile has been taken out from or driven into the garage and it is desired to close the doors, a slight pull is given to the chain 28, whereupon the gripping plate is moved from the position shown in Fig. 4 to that shown in Fig. 5 and is held in this position by means of the lever 16, thereupon the rod 14 can move freely into the pipe 5 and this permits the door to be closed. The cam member 21 is so positioned on the rod that when the door is fully closed, it will raise the lever 16 and release the gripping plate so as to permit the parts to return to normal position.

For the purpose of permitting the door to move to some extent without producing excessive strains on the hinges, a spring 33 has been put in place between the bracket 34 which is secured to the door and the washer 35 that surrounds the end of rod 14 and which is held in place by means of a pin 36. Another pin 37 extends through the extreme end of rod 14 and keeps it from being withdrawn from the bracket 34. When a gust of wind strikes the door, it can move slightly because the spring 33 will yield. The spring 31 can be dispensed with as it is not essential to the operation of the device, but may be desirable in some installations.

From the above description it will be apparent that I have produced a simple and substantial door stop that can be readily applied to any hinged door and which will automatically latch the door in open position and which will be effective at any point between closed and fully open position. It will also be apparent that I have produced a very simple gripping means that can be quickly released and which will be automatically returned to normal position when the door is closed.

Having described the invention what I claim as new is:

1. In combination with a door frame and a door hingedly connected therewith, means for holding the door in open position, comprising, in combination, two telescopically connected members, one end of one of the members being pivotally connected with the door frame and one end of the other member being connected with the door, gripping

means carried by one of the members for preventing the two members from collapsing while permitting them to extend, means for moving the gripping means to inoperative position, means for latching the gripping means in inoperative position while the door is moved to closed position and means for releasing the latching device when the door reaches closed position.

2. In combination with a door frame and a door hingedly connected therewith, means for holding the door in open position, comprising in combination, two telescopically connected members, one of which is tubular and the other of which is adapted to extend into the tubular member, one end of the tubular member being pivotally connected with the door frame, one end of the other member being connected with the door, a gripping device carried by the free end of the tubular member and cooperating with the other member to permit extension of the two members, but prevent them from being collapsed, means for moving the gripping device to inoperative position, a latching device for holding it in inoperative position while the door is moved to closed position and means for releasing the latch when the door reaches closed position.

3. In combination with a door frame and a door hingedly connected therewith, means for holding the door in open position, comprising, in combination, two telescopically connected members, one of which is tubular and the other of which is adapted to extend into the tubular member, one end of the tubular member being pivotally connected with the door frame, one end of the other member being connected with the door, a gripping device carried by the free end of the tubular member and cooperating with the other member to permit extension of the two members, but prevent them from being collapsed, means for moving the gripping device to inoperative position, a latching device for holding it in inoperative position while the door is moved to closed position, means for releasing the latch when the door reaches closed position, and a resilient connection between the door and the holding device whereby the door may move towards closed position to a limited extent.

4. In combination with a door frame and a door hingedly connected therewith, means for holding the door in open position, comprising a tubular member pivotally connected at one end to the top of the door frame, a rod extending into the tubular member and movable longitudinally therein, one end of the rod being connected with the door, a gripping device connected with the free end of the tubular member, said gripping device comprising a plate having a hole through which the rod extends, a fulcrum for the plate at one side of the rod, a spring asso-

ciated with the plate and tensioned to move it against the fulcrum, a latching member adapted to engage one end of the plate and hold it in a plane perpendicular to the axis of the rod, and means comprising a cam carried by the rod for releasing the latch when the door is moved to closed position.

5. A door stop comprising, in combination, a tubular member having means at one end for attaching it to a door frame, a gripping device secured to the other end thereof, said gripping device comprising an elongated tubular body member having a transverse opening, a plate extending through the opening and provided with a hole, a rod extending through the tubular body member, through the hole in the plate and into the tubular member, a spring operatively associated with the plate for moving it into a plane inclined with respect to the axis of the rod, a latch member pivotally connected with the tubular body member for engaging one end of the plate and holding it in inoperative position, means comprising a cam connected with the rod and adapted when in one position to engage the latch and move it into inoperative position, and means for attaching the rod to the door whereby when the door is opened the rod will be pulled outwardly from the tubular member, and when the door is closed it will be moved inwardly into the tubular member.

In testimony whereof I affix my signature.
WALTER E. WEGNER.
